ART OF CONVERTING HYDROCARBON OILS

Robert F. Ruthruff, Hammond, Ind., assignor to
Standard Oil Company, Whiting, Ind., a cor-
poration of Indiana

Application August 4, 1930, Serial No. 472,973

2 Claims. (Cl. 196—49)

The present invention relates to improvements in the production of gasoline or other desired light hydrocarbons from heavier hydrocarbon oils, and more particularly to such conversion processes involving a cycle of operations whereby fresh stock introduced into the system is completely converted into the desired light hydrocarbon products, such as gasoline, except for such portions thereof as are converted to a solid residuum or coke and to gas.

10 The invention will be fully understood from the following description, illustrated by the accompanying drawings, in which:

15 Figure 1 is a diagrammatic showing of a layout of apparatus for carrying the invention into effect; and

Fig. 2 is a diagrammatic showing of a modified layout of apparatus embodying the invention.

20 Referring more particularly to Fig. 1 of the drawings, the numeral 5 indicates a receiving or mixing tank, to which the fresh stock for the system, suitably a heavy residual oil, is supplied through the line 6. The heavy oil thus employed may suitably be a residuum, for example, of the character of one representing 25% or less of a Mid-Continent crude and derived from a distillatory process in which little or no cracking takes place, such as vacuum or steam distillation.

25 The residuum thus fed to the mixing tank 5, together with other residual oil products supplied thereto as hereinafter set forth, is removed through the line 7 and forced by pump 8 through the pipe still furnace 9, in which it is heated to a high cracking temperature, say 840 to 950° F. and preferably 900 to 910° F., with a low outlet pressure, suitably approximately atmospheric or up to 30 lbs. gauge, the operation being preferably as described in the prior application of Robert E. Wilson, Serial No. 329,419. The 30 heated oil leaving the pipe still 9 enters the manifold 10, from which it is discharged through one or more of lines 12, 13, 14 into one or more of the enlarged chambers or drums 15, 16 and 17 respectively. In the drums, which are maintained at elevated cracking temperatures, for example, by the heat of the entering oil products, conversion into a substantially solid residue or coke and into gaseous and vaporous products is completed, substantially as described in the prior 35 application of Robert E. Wilson, hereinbefore referred to. The conduits 12, 13 and 14 are suitably provided with connections opening into the respective drums at different levels, so that the point of introduction of the entering oil can be raised, if desired, as the level of coke in the

drum rises. The heated oil may be fed into the drums 15, 16 and 17 in rotation, in any two or in all three simultaneously, as desired. Preferably, they are employed in rotation, to permit continuous operation of the pipe still and the required cleaning of the respective drums as they become filled.

30 Vapors from the drums 15, 16 and 17, or such thereof as are in use, pass out through valved connections 18, 19 and/or 20 respectively to a manifold 21, from which they pass through line 22 to the lower portion of a suitable fractionating column 23, which may be of any desired type, for example, a bubble plate column. In this column the heavier portions of the vapors are 35 condensed, the lighter vapors containing the desired low boiling product together with gas passing out through the vapor line 24 to a suitable condenser 25, in which the desired products are condensed and the cooled products discharged 40 through line 26 into a collector and gas separator 27.

45 The heavier condensed portions or reflux formed in the fractionating column 23 are collected therein and discharged through the valved line 28 to a second mixing tank or receiver 29, suitably lagged to prevent loss of heat. If desired, the heavier fractions condensed and collected in the fractionating column 23, and which may include some entrained tar, may be separately removed therefrom through the valved line 30 and returned to the mixing tank 5, to be returned to the pipe still 9 and the remainder of the system with the other stocks introduced thereto. It will be understood, of course, that the mixing tank 5 may likewise be suitably lagged or insulated to prevent loss of heat therefrom.

50 It will be understood likewise that the fractionating column 23 will be at approximately the same pressure as or at a slightly lower pressure than that prevailing in the enlarged drums 15, 16 and 17, for example, at approximately atmospheric pressure or at a pressure up to about 30 lbs. gauge.

55 The fractions condensed in the fractionating column 23 and discharged into the mixing tank 29 are removed from the latter through the line 31 by pump 32 and forced through pipe still 33, in which they are brought to a cracking temperature, preferably in excess of 850° F. Although substantial pressures may be employed at the outlet of the pipe still furnace 33, it is preferred that the pressure conditions therein be such that the oil passing therethrough is completely vaporized and substantial cracking there-

of effected in the vapor phase. The products from the pipe still or cracking coil furnace 33 pass through the line 34 into the enlarged cracking chamber, 35, in which further cracking takes place. The conditions prevailing in the cracking coil 33 and the cracking chamber 35 may suitably be such as to produce substantial cracking in the vapor phase in both the cracking coil and the cracking chamber, for example, conditions such as are more fully set forth in the pending application of Harold R. Snow and Frederick W. Sullivan, Jr., Serial No. 427,216, filed February 10, 1930. For example, with outlet temperatures for the cracking coil as hereinbefore set forth, pressures from atmospheric up to 400 lbs. may prevail in the cracking chamber 35. Suitable temperatures and pressures are, for example, a coil outlet temperature of 925 to 950° F. with a pressure in the enlarged chamber of 175 to 300 lbs., the cracking chamber being lagged or insulated to prevent loss of heat therefrom.

The gaseous and liquid products of cracking are discharged from the cracking chamber 35 through line 36 provided suitably with a pressure reducing valve 37, and enter a separating chamber 38. The latter may be provided with baffle plates of any suitable design (not shown), for example, doughnut and disk plates or bubble cap plates.

The heavy liquid products separated in the separating chamber 38, which may suitably be at a temperature of 650 to 750° F., are discharged through the line 39 and pass to the mixing tank 5, wherein they are admixed with the fresh stock entering through the line 6 and from which they pass with the latter to the pipe still furnace 9, for treatment as hereinbefore set forth. The vapor products from the separating chamber 38 pass through the vapor line 40 into the fractionating column 41, wherein they are cooled to condense the portions thereof heavier than the desired light gasoline or gasoline-containing products. The condensate from the vapor products formed in the fractionating column 41 may be discharged through the line 42, being, for example, at a temperature of 600 to 700° F., and may then be passed to the mixing tank 29, to be mixed therein with the reflux condensate formed in the fractionating column 23 and passed to the cracking coil furnace 33. The vapors and gases uncondensed in the fractionating column 41 pass out through the valved line 43, which joins the line 24 leading to the condenser 25 and separator 27. The desired low boiling products in the vapors are thus condensed and collected with those passing out of the fractionating column 23.

The fractionating column 41 and the separating column 38 may suitably be maintained at pressures approximating those prevailing in the cracking chamber 35 or lower, and are preferably maintained at atmospheric pressure or a pressure intermediate that prevailing in the fractionating column 23 and condenser 25 and that prevailing in the cracking chamber 35. Thus, with pressures of from about atmospheric to about 30 lbs. gauge in the chambers 15, 16 and 17 and the fractionating column 23, pressures between approximately atmospheric and about 65 lbs. gauge have been found suitable in the separating chamber 38 and the fractionating column 41.

It will be noted that in operation conducted as hereinbefore described, the system may be fed with a heavy residual stock, and that the products issuing from the system, apart from the coke formed therein, and the desired low boiling dis-

tillate product are entirely gaseous. It will be readily apparent, that if desired, the operation may be modified to secure heavy residual products.

In Fig. 2, there is illustrated an arrangement of apparatus wherein a modified form of the operation may be carried out.

In the operation illustrated in Fig. 2, a fresh oil, which may be a mixture of light and heavy or residual constituents, such as a crude oil, 10 after suitable preheating as hereinafter described, is fed through line 50 to the treating or mixing tank 51, suitably insulated to prevent loss of heat. In the event that light portions of the stock thus supplied are vaporized, the vapors 15 thereof may be removed from the feed tank 51 through the line 52, leading to a suitable condenser and gas separator (not shown). The pre-heated liquid from the tank 51 is drawn therefrom through line 53 by pump 54, by which 20 it is forced through a pipe still 55, in which it is heated to a temperature sufficient to vaporize a substantial portion thereof. If desired, steam may be supplied to the oil entering the coil, for example, through line 55a. In the pipe still fur- 25 nace 55, the oil is heated to a temperature such that a sufficient proportion thereof will be vaporized to leave a residue of, say, 27° A. P. I. or lower, for example, a residue corresponding to a 25% or lower residue from Mid-Continent crude 30 oil.

The products from the pipe still 55 pass through line 56 to a separating drum 57, in which the unvaporized portions are separated from the vapors and gases. The latter pass out through 35 vapor line 58 to a fractionating column 59, in which the heavier portions of the vapors are condensed; for example, the gas oil and heavier fractions. If desired, kerosene fractions may be condensed therewith, or may be permitted to pass 40 out through the vapor line 60 with the lighter fractions, to suitable fractional condensers, not shown, wherein further fractional condensation of the light vapors may be effected.

The unvaporized fractions collected in the 45 separating chamber 57 are withdrawn therefrom through line 61 by pump 62 and forced through line 63 to the hot supply tank or mixing tank 64, for treatment as hereinafter set forth.

The mixing or feed tank 64 is suitably insulated 50 or lagged to prevent loss of heat therefrom. The heavy residual oil is withdrawn from the tank 64 through line 65 by pump 66 and forced through the heating coil 67, from which it is discharged through line 68 to the manifold 69. From the latter the heated oil products are passed through lines 70, 71 and 72 into one or more of the coking drums 73, 74 and 75 respectively, the operation conducted in the coil 67 and the drums 73, 74 and 5 being similar to that hereinbefore described in 60 connection with the coil 9 and the drums 15, 16 and 17 in the operation shown in Fig. 1.

Coke collects in the drums 73, 74 and 75 or such thereof as are in use. The vapor products from these drums or those of the drums which are in 65 use, pass out through the corresponding lines 76, 77 and/or 78 to the vapor manifold 79, from which they pass through the line 80 into the fractionating column 81, wherein the vapors are cooled, so as to condense the heavier portions thereof, the uncondensed lighter portions comprising the desired 70 low boiling fractions and gas passing out through the vapor line 82 to any suitable condenser and gas separator (not shown).

The condensate formed in the fractionating 75

tower 81, or the greater portion thereof, is withdrawn through the valved line 83 and passes to the insulated mixing chamber 84, to which may also be supplied the condensate separated in the 5 fractionating column 59 as hereinbefore set forth. This condensate may be withdrawn from the fractionating tower 59 through the valved line 85, by which it is conveyed to the mixing or feed tank 84.

10 If desired, a small heavier fraction of the condensate formed in the fractionating column 81, which may include any entrained tar entering the latter, may be withdrawn through the line 86 and discharged into the mixing tank 64, to pass 15 through the pipe still 67 with the heavy residue, as hereinbefore described.

The heavy distillate fractions from the fractionating column 81, together with those from the fractionating column 59, are withdrawn from the 20 feed tank 84 through the line 87 by pump 88 and forced through the cracking coil furnace 89, from which the heated products pass through the line 90 to the cracking chamber 91, the operation in the cracking coil 89 and cracking chamber 91 being similar to that taking place in the cracking coil 33 and cracking chamber 35 in the operation of Fig. 1, as hereinbefore described. The products from the cracking chamber 91 pass out through the line 92, in which may be provided the 25 pressure reducing valve 93, to a separating column 94, in which a separation of vapor and liquid products is effected, similar to that occurring in separating column 38 in the embodiment illustrated in Fig. 1. The separated residual liquid 30 or tar passes out of separating column 94 through line 95 and is discharged into the mixing or feeding tank 64 from which the heating coil 67 is fed.

The vapors pass out of the separating column 94 through line 96, and enter the fractionating column 81 at an intermediate point, cooling and fractionation thereof being effected in said column together with the cooling and fractionation of the vapors received from the coking chambers 73, 74 and/or 75. The heavier fractions of the vapors from the separating column 94 are thus simultaneously condensed and commingled with those from the cracking chambers, as hereinbefore set forth, and the resulting condensate passes together through the line 83 to the feed tank 84 for the cracking coil 89. Similarly, the uncondensed vapors and gas derived from the separating column 94 likewise pass out of the fractionating column 81 through the line 82 to suitable condensers and gas separators, not shown.

55 A suitable pressure release valve 97 is provided in the line 96 in the event that the separating column 94 is operated at a substantially higher pressure than that prevailing in the fractionating column 81, since it is readily apparent that pressure in the latter may not exceed that prevailing in the coking chambers 73, 74 and 75 and will therefore ordinarily be not higher than 30 lbs. gauge, whereas the separating column 94 may be operated at pressures not exceeding those prevailing in the cracking chamber 91, which may be substantially higher. The pressure in the separating column is preferably not higher than about 65 lbs. gauge.

In order to secure the desired cooling action in

the fractionating column 81 and the separating column 94, cooling coils 98 and 99 respectively may be provided therein, and the heat abstracted thereby may be utilized in preheating the crude. 5 Crude or mixed oil is supplied to the heating tank 51, to be fed to the heating or distilling coil 55. For instance, the crude oil or other oil fed to the system may be passed through line 100 to the coil 98 in the fractionating column 81; thence through line 101 to the coil 99 in the separating column 10 94; and from the latter through the line 50 to the feed tank 51.

Although the present invention is described in connection with specific details of various embodiments thereof, it is not intended that these 15 shall be regarded as limitations upon the scope of the invention, except in so far as included in the accompanying claims.

I claim:

1. The method of treating crude oil which comprises heating said oil to a temperature sufficient to vaporize a portion thereof and leave unvaporized a residue having a gravity of 27° A. P. I., or lower, dephlegmating resulting vapors in a first fractionating zone to produce a condensate, heating said residue to a cracking temperature under low pressure and introducing it into a coking zone wherein separation of vapors occurs, dephlegmating these vapors in a second fractionating zone 25 and separating therefrom a heavy condensate in quantities only great enough to remove entrained tar, and a larger quantity of intermediate condensate, withdrawing said heavy condensate from said second fractionating zone and combining it with said residue for heating, mixing said condensate first-mentioned with said intermediate condensate, cracking the mixture in the vapor phase, under a pressure materially higher than said low pressure, dephlegmating the resulting vapors to separate a condensate, combining the 30 separated condensate with said residue prior to the heating thereof to cracking temperature, combining the dephlegmated vapors with the vapors from the coking operation to be further dephlegmated therewith, and removing uncondensed 35 dephlegmated vapors and condensing them as a desired product.

2. The method of treating heavy residual hydrocarbon oil which comprises heating said oil to a coking temperature, introducing the heated oil 50 into a coking zone wherein coking occurs and vapors are liberated, fractionating said vapors to separate therefrom substantially only the entrained tar, further fractionating the vapors to separate condensate heavier than the desired 55 final product as an intermediate fraction, cracking said intermediate fraction in the vapor phase, separating the resulting cracked products into vapors and a residue while out of contact with said vapors undergoing fractionation and in a zone 60 separate from said coking zone, combining the vapors separated from said resulting cracked products with said vapors first-mentioned after removal of entrained tar, combining said entrained tar and said residue with said heavy residual oil and condensing the completely fractionated vapors as a desired final product.

ROBERT F. RUTHRUFF.
